UNITED STATES PATENT OFFICE.

EDGAR D. TILLYER, OF SOUTHERBRIDGE, MASSACHUSETTS, ASSIGNOR TO AMERICAN OPTICAL COMPANY, OF SOUTHERBRIDGE, MASSACHUSETTS, A VOLUNTARY ASSOCIATION OF MASSACHUSETTS.

OPHTHALMIC LENS.

No Drawing.

Application filed May 5, 1922. Serial No. 553,758.

To all whom it may concern:

Be it known that I, EDWARD D. TILLYER, a citizen of the United States, residing at Southbridge, in the county of Worcester and 5 State of Massachusetts, have invented certain new and useful Improvements in Ophthalmic Lenses, of which the following is a specification.

This invention relates to improvements 10 in ophthalmic lenses, and has particular reference to a novel and improved commercial ophthalmic lens and to the art or process of producing the said article.

Ophthalmic lenses at the present day are 15 of many different grades and types, depending on the manufacturer producing the same, the accuracy and processes of manufacture, and the particular type of lens involved. At the present time there are marketed certain ophthalmic lenses of very high 20 grade and expensive type resulting from the use of the highest possible grade of workmanship, material and equipment, while at the same time there are also on the market numerous imitations of a much inferior 25 quality. As an ophthalmic lens is a structure designed to be placed on the face and employed for visual purposes, it has hitherto been found impossible to so mark or designate the lens that the purchaser could be 30 sure of the grade and quality of product, the name of the manufacturer, or the like, since any such designations, if applied to the lens, would be either temporary and liable to be removed during the necessary 35 cleaning before delivery of the lens to the patient, or, if attempted to be permanently applied, would be of a visible character tending to interfere with vision or with the 40 appearance of the mounting so as to cause the same to be refused by the purchaser.

It is, therefore, one of the principal objects of the present invention to provide as 45 a novel article of manufacture, a lens which shall be provided with a permanent mark or designation, that is to say, a designation which will not be removed or impaired by the ordinary cleaning to which lenses are subjected and yet which will be invisible under ordinary service conditions.

A further object of the invention is the provision of a novel and improved art or process of producing these designations on the lens.

Other objects and advantages of the present invention should be readily apparent by reference to the following specification, and it will be understood that I may make any modifications in the structure or steps hereinafter described within the scope of the appended claims without departing from or exceeding the spirit of my invention.

In the carrying out of my invention I first construct a lens from ordinary crown or flint glass, or a suitable combination of both, surfacing it in the usual manner on either one or both faces as may be preferred.

After the lens has been finally finished on at least one surface it is in condition for the carrying out of our process, which consists in applying to the finished surface of the lens, either by pen, brush, rubber stamp, stencil, or other desired manner, suitable designations, such as the trade-mark, name 70 of the manufacturer, or the like. While I have found that several different substances may be employed for this purpose, I would give as an example of one which I have found quite satisfactory, phosphoric acid. 75 The acid having been applied to the lens surface and left there a predetermined period, I may then, if desired, directly remove the acid, which as is known is of what is known as non-drying type, that is, it will not 80 dry off under ordinary climatic conditions, this removal being done as by washing to prevent undue spreading of the acid over the surface of the lens during removal except in very dilute form.

While as stated I may directly wash off the acid, I have found that it is preferably after its application to subject the lens to a heating action which will aid in the result to be accomplished. This result consists in 90 changing the hydroscopic properties of the surface of the lens or modifying its surface tension. The purpose of this modification of the surface of the glass to this extent resides in the fact that this surface modification is not an eating into or destroying of the polish of the surface of the glass which is visible under ordinary conditions, but is one which will affect the physical or chemical condition of the surface in such 100 manner that upon subjecting the same to slight moisture, such as the moisture of the breath when blowing upon the glass, the

difference in surface will cause the moisture, as is usual, to condense in globules but the condensated globules on the modified part which has been treated by the acid will be 5 different as to size from those on the remainder of the lens, with the result that light striking the surface will be differently affected so that the letters, words, or the like, will clearly stand out as distinct from 10 the remainder of the lens and may be readily observed so long as the surface moisture endures but will entirely disappear as the lens surface dries off.

I have found by the production of these 15 lenses that they may be subjected to indefinite washing, wiping, or other cleaning actions, without impairing the visibility of the designation marks. I refer to the use of phosphoric acid as particularly desirable 20 in this connection since I have found this is one of the substances which will tend to add to the glass surface rather than to subtract therefrom, that is to say, there is no modification of the surface perceptible in 25 any ordinary manner yet clearly perceptible

under the hydroscopic test, but the action is apparently a changing of the glass at these points to what is known as phosphoric glass, a recognized form of glass in the industries, having much greater hydro- 30 scopic properties than do more common forms of glass, such as employed in the manufacture of spectacle lenses.

I claim:

1. An ophthalmic lens having a polished 35 refracting lens surface and a spot on said surface having a different reaction to vapor than the rest of the surface, and being without refractive effect on the lens surface in the absence of vapor.

2. An ophthalmic lens having a non-phosphoric body portion having a polished refracting lens surface thereon, and a spot of phosphoric glass on the refracting surface, said spot being without refractive 45 effect on the lens surface in the absence of vapor and having a different reaction to vapor than the non-phosphoric portion.

EDGAR D. TILLYER.
